CLAIM

We claim the ornamental design for a force sensor, as shown and described.

DESCRIPTION

FIG. 1 is a front side elevation view of a force sensor embodying our design;

FIG. 2 is a rear side elevation view of the force sensor shown in FIG. 1;

FIG. 3 is a right side elevation view of the force sensor shown in FIG. 1;

FIG. 4 is a left side elevation view of the force sensor shown in FIG. 1;

FIG. 5 is a top plan view of the force sensor shown in FIG. 1;

FIG. 6 is a bottom plan view of the force sensor shown in FIG. 1; and,

FIG. 7 is a perspective view of the force sensor shown in FIG. 1.
